HIS ATTORNEY.

UNITED STATES PATENT OFFICE

JOHN WEGNER, OF THORP, WISCONSIN

WHIPPING DEVICE

Application filed March 10, 1930. Serial No. 434,831.

This invention relates to certain novel improvements in whipping devices and has for its principal object the provision of an improved construction of this character which will be highly efficient in use and economical in manufacture.

Among the several objects of this invention is to provide a whipping device adapted to be confined in a predetermined location where it is undesirable for cows and other animals to tramp about.

Other objects will appear hereinafter.

The invention consists in the novel combination and arrangement of parts to be hereinafter described and claimed.

The invention will be best understood by reference to the accompanying drawings, showing the preferred form of construction and in which:

20 Fig. 1 is a perspective view of the invention;

Fig. 2 is a plan view of the same;

Fig. 3 is a cross-sectional detail view of the same taken substantially on the line 3—3 on 25 Fig. 2;

Fig. 4 is an end view of the invention; and

Fig. 5 is a sectional detail view taken substantially on the line 5—5 on Fig. 2.

Referring to the drawings in which the preferred form of construction is illustrated the device comprises two end block members 10 and 11. These block members are arranged in spaced relation with respect to each other and carry at corresponding end portions a 30 transversely extending bar 12 having mounted thereon for rotation therewith collars 13. These collars 13 have connected thereto in any suitable manner as at 14 a bumper or whipper bar 15, the bight portion of which is adapted to extend above and transversely 35 between the end blocks 10 and 11.

The ends 16 of the bar 12 extend through openings 17 formed in the blocks 10 and 11 and secured in slots 18. Formed in these end 40 portions 16 are upstanding lugs 19 which are adapted to be engaged by plunger fingers 20 slidably carried by brackets 21 secured to the blocks 10 and 11 by means of suitable securing elements 22.

50 Arranged upon the plunger fingers 20

within the brackets 21 are expansion springs 23 having corresponding end portions abutting the limbs 24 of the brackets 21 and opposite corresponding end portions abutting shoulders 25 carried by the plunger fingers 20. 55

The ends 26 of these fingers are pivotally connected by means of pintles 27 to links 28 having connection as at 29 with arm 30 secured in slots 31 formed in the end portions 32 of a rocker bar 33. These end portions 32 are projected through openings 34 formed in the blocks 10 and 11 so as to rotatably support the rocker bar 33 in parallel spaced relation with respect to the bar 12.

Secured to the rocker bar 33 is a step 35 positioned between the end blocks 10 and 11. This step is secured to the rocker bar 33 by means of clamping structures 36 of any approved construction.

Secured to the rocker bar 33 are upstanding arms 37 and secured to the extremities of these arms 37 are the end portions 38 of coil springs 39. The opposite ends of these springs 39 are connected to the bar 12 by means of nut bearing bolts 40. 75

Formed in the collars 13 are sockets 41 into which are adapted to project latch pins 41' slidably carried by brackets 42 connected to the end plates 10 and 11 and urged in the direction toward the sockets 21 by 80 means of springs 43 engaging collars 44 carried by the pins. The pins are pivotally connected to the rocker bar 33 by link structures 45 which are in turn connected to arms 46 secured through the ends of the rocker bar 85 33 and held in place by means of nuts 47.

In use, the end blocks 10 and 11 are imbedded in the ground in an area where it is not desired to have cattle tramp upon, with the bumper or whipper bar in a vertical position. Should the cattle encroach upon the restricted area where the device is located the foot of the animal will engage the step 35 and the weight thereon will rock the arm 33 so as to place the springs 39 and the springs 23 under tension. During the rocking of this bar 33 movement will be imparted to the latch pins 41' through the link structures 45 so as to disengage these pins from the sockets 41. Immediately upon this disengagement 100

of the pins from the sockets 41 the springs 39 being under tension will rotate the bar 12 so as to bring the bumper or whipper bar into whip-like action against the limb or legs 5 of the animal and thereby tend to frighten the animal and cause the same to leave the restricted area.

As soon as the animal's foot is removed from the step the springs 23 being under tension 10 will rotate the rocker bar 33 in an opposite direction and the pins 20 will engage the arms 19 and reseat the device in the position shown in Fig. 1.

So as to limit retroactive movement of the bar 12 there is provided stop lugs 48 adapted 15 to engage the lower end portions 49 of the limbs 50 of the bumper or whipper bar.

My device may be placed at the point of entrance to an area which is muddy so as to 20 keep the cattle from grazing or roaming upon the muddy area.

While I have illustrated and described the preferred form of construction for carrying my invention into effect, this is capable of 25 variation and modification, without departing from the spirit of the invention. I, therefore, do not wish to be limited to the precise details of construction set forth, but desire to avail myself of such variations and modifications as come within the scope of the appended claims.

Having thus described my invention what I claim as new and desire to protect by Letters Patent is:

35 1. A device of the character described including two rotatable members arranged in parallel spaced relation with respect to each other, block members supporting said rotatable members for rotation, resilient means 40 for urging rotation of one of said members in one direction and having connection with the other of said rotatable members, a step carried by said other of the rotatable members for rotating said other of the rotatable 45 members to place said resilient means under tension to rotate said one of the rotatable members at a predetermined time, latch means operable by rotation of said other of the rotatable members for holding said one of rotatable members against rotation by action 50 of said resilient means, and a whipper bar carried by said one of the rotatable members.

2. A device of the character described including two rotatable members arranged in 55 parallel spaced relation with respect to each other, block members supporting said rotatable members for rotation, resilient means for urging rotation of one of said members in one direction and having connection with 60 the other of said rotatable members, a step carried by said other of the rotatable members for rotating said other of the rotatable members to place said resilient means under tension to rotate said one of the rotatable 65 members at a predetermined time, latch means

operable by rotation of said other of the rotatable members for holding said one of rotatable members against rotation by action of said resilient means, a whipper bar carried by said one of the rotatable members, and means for rotating said rotatable members in corresponding directions opposite to the rotation of said one of the rotatable members by action of said resilient means.

3. A device of the character described including two rotatable members arranged in parallel spaced relation with respect to each other, block members supporting said rotatable members for rotation, resilient means for urging rotation of one of said members in one direction and having connection with the other of said rotatable members, a step carried by said other of the rotatable members for rotating said other of the rotatable members to place said resilient means under tension to rotate said one of the rotatable members at a predetermined time, latch means operable by rotation of said other of the rotatable members for holding said one of the rotatable members against rotation by action of said resilient means, a whipper bar carried by said one of the rotatable members, and means for rotating said rotatable members in corresponding directions opposite to the rotation of said one of the rotatable members by action of said resilient means.

4. A device of the character stated including two rotatable members arranged in parallel spaced relation with respect to each other, block members supporting said rotatable members for rotation, resilient means for urging rotation of one of said members in one direction and having connection with the other of said rotatable members, a step carried by said other of the rotatable members for rotating said other of the rotatable members to place said resilient means under tension to rotate said one of the rotatable members at a predetermined time, latch means operable by rotation of said other of the rotatable members for holding said one of the rotatable members against rotation by action of said resilient means, and a whipper bar carried by said one of the rotatable members, and means for limiting rotation of said one of said rotatable members in the direction by action of said resilient means.

5. A device of the character described including two rotatable members arranged in parallel spaced relation with respect to each other, block members supporting said rotatable members for rotation, spring members having connection to said rotatable members for urging rotation of one of said members in one direction and having connection with the other of said rotatable members, a step carried by said other of the ro-

tatable members for rotating said other of the rotatable members to place said resilient means under tension to rotate said one of the rotatable members at a predetermined time, latch means operable by rotation of said other of the rotatable members for holding said one of rotatable members against rotation by action of said resilient means, and a whipper bar carried by said one of the rotatable members.

6. A device of the character described including two rotatable members arranged in parallel spaced relation with respect to each other, block members supporting said rotatable members for rotation, spring members having connection to said rotatable members for urging rotation of one of said members in one direction and having connection with the other of said rotatable members, a step carried by said other of the rotatable members for rotating said other of the rotatable members to place said resilient means under tension to rotate said one of the rotatable members at a predetermined time, latch means operable by rotation of said other of the rotatable members for holding said one of the rotatable members against rotation by action of said resilient means, a whipper bar carried by said one of the rotatable members, and means for rotating said rotatable members in corresponding directions opposite to the rotation of said one of the rotatable members by action of said resilient means.

In testimony whereof I affix my signature.
JOHN WEGNER.
